UNITED STATES PATENT OFFICE.

FREDERICK G. KEYES, OF BOSTON, MASSACHUSETTS, ASSIGNOR TO ARTHUR A. NOYES,
TRUSTEE, OF BOSTON, MASSACHUSETTS.

SEAL FOR VACUUM APPARATUS.

1,159,335.

Specification of Letters Patent.

Patented Nov. 2, 1915.

Application filed March 6, 1913. Serial No. 752,316.

To all whom it may concern:

Be it known that I, FREDERICK G. KEYES, a citizen of the United States, and resident of Boston, in the county of Suffolk and 5 State of Massachusetts, have invented new and useful Improvements in Seals for Vacuum Apparatus, of which the following is a specification.

My invention relates to improvements in 10 seals for vapor electric apparatus, and is more particularly addressed to the construction of hermetic seals for introducing an electric current into a vapor electric apparatus and which shall be permanent and reliable during the operation of the apparatus 15 at elevated as well as at ordinary temperatures.

My invention is well illustrated in connection with arc lamps of the mercury 20 vapor type. Such lamps possess a high efficiency and are well adapted to many commercial purposes, for illumination as well as others. It has been found that by inclosing the arc in a chamber of highly resist- 25 ant material, such as fused silica, the efficiency and general adaptability of the lamp is greatly increased. Much difficulty has hitherto been experienced in the introduction of leads into containers constructed of 30 fused silica. In commercial practice conical plugs of nickel steel are ground into a heavy tube of fused silica, and these plugs are further tightened by means of liquid mercury. Such seals, however, have proved 35 very unsatisfactory in practice. Recently, in a copending application by C. A. Kraus, Serial No. 688,815, filed April 5, 1912, a hermetic seal has been developed which is adapted to fused silica containers, and 40 which possesses many advantages over seals hitherto constructed. This seal consists of a tubular metal member, such as platinum, which is sealed through a fusible glass of much lower coefficient of expansion than 45 that of the metal tube. When a container of fused silica is employed, the glass, through which the metal tube is sealed, has a coefficient of expansion practically the same as that of fused silica, *i. e.* a coefficient so low 50 that under very severe treatment, as for instance, quenching in water, the junction between the glass and the fused silica retains its integrity. These seals are very useful for manifold purposes, but in the case of 55 certain mercury vapor arc lamps, the metal

tube of the seal together with the contained liquid mercury and mercury vapor are heated to a very high temperature, sometimes as high as 360° centigrade. Under these conditions the tendency of the mercury to alloy with the metal tube, as platinum for example, is very greatly increased. If such alloying takes place, the metal of which the tube is constructed loses its ductility and plasticity which is an essential feature of the seal in question. For, since the metal tube has a higher coefficient of thermal expansion than the surrounding glass, it is in a state of tension and this state is of great utility so long as it can be maintained under conditions wherein the superficial adhesive force between the glass and the metal is sufficiently great to overcome the tensile stress in the metal tube itself. To insure these conditions, a very soft or 60 ductile metal such as platinum is employed. When, however, at high temperatures, the mercury alloys with the metal, the said metal loses its necessary condition of plasticity and ductility, the necessary stress conditions as between the glass and the metal tube are no longer fulfilled and the seal 65 loses its hermetic vacuum tight quality.

My invention is addressed to providing means for preventing the liquid metal or 70 metal vapor, as for example mercury, from coming into contact and alloying with the metal tube, for if the alloying of the mercury with the metal tube can be prevented, the metal tube will retain its original condition of ductility and plasticity and the seal 75 will retain its hermetic and vacuum tight qualities.

My invention will be better understood in connection with the accompanying figures which illustrate the method of practising the same, and in which:

Figure 1 represents a longitudinal section of a seal embodying my invention; Fig. 2 represents a sectional view of another seal embodying my invention but differing from Fig. 1 in specific detail; Fig. 3 represents a sectional view of another seal embodying my invention but differing from the preceding seals in specific details; Fig. 4 represents a section of still another seal embodying my invention with certain variation of specific detail; and Fig. 5 represents a section of still another seal embodying my invention with variation as to specific detail.

Referring now to Fig. 1, A is a tube of material which is vitreous in nature. By way of illustration we shall assume that in this specific instance it is fused silica. B is a thin metallic tubular member of highly ductile or plastic properties, which we may in this specific instance assume to be platinum. C is constructed of vitreous material possessing a coefficient of expansion less than that of the metal member B, and approaching that of the vitreous member A very closely. When the member A is constructed of fused silica and the member B of platinum, as I have assumed for the sake of illustration, I recommend that the member C be constructed of a composition comprising silica (SiC_2) and boric acid (B_2O_3) in its essential elements. This composition of matter has been fully described by Keyes and Kraus in a co-pending application, Serial No. 752,374, filed concurrently with the present application. The material of which the member C is constructed as described above, possesses a melting point sufficiently low so that it may be applied and sealed to the platinum tube B without danger of melting the same. At the same time the adhesive forces between the tubular member B and the surrounding vitreous member C are such that no forces can arise in the tubular member itself which are able to overcome the intimacy of contact between the contiguous surfaces of B and C, and the permanent integrity of the juncture between the two members is thus assured. The member C is in turn sealed to tube A at the point D. The coefficient of expansion of the member C must approach that of the member A sufficiently closely to render the juncture at D a secure and permanent one. If the container material A has a sufficiently low melting point, it may be sealed directly to B and C may be omitted. For most purposes it is preferable that the tubular metallic member B should be provided with a metallic lead F attached to the outer end of the tube B and passing through B, in which case the tube B does not itself act in carrying the current. In some cases, however, it is sufficient to employ the tube B itself as a conductor for introducing the current as shown in Fig. 2, the inner end of the platinum tube B being closed and provided with a lead F. The end of the lead F is joined to the end of the tube B by fusion or by soldering. The end of the tube A is joined to the container into which it is desired to introduce current. This container comprises a quantity of more or less volatile metal, such as mercury, through the vapor of which the arc passes. The tube A is therefore either filled with metal or metal vapor. As already set forth, this metal tends to alloy with the metallic tube B, particularly when, as in the quartz mercury arc

lamp, the apparatus is operated at elevated temperatures.

I have found, and this constitutes an important element in my invention, that by introducing a suitable means to prevent or hinder the flow or diffusion of the metal or the metal vapor into the neighborhood of the tube B, this deleterious alloying may be prevented or so hindered that a seal of this type may be employed in operating quartz mercury arc lamps for extended periods of time without visible or detectable impairment of the seal.

It is to be understood that the term "quartz" as employed in connection with a vapor electric lamp signifies fused silica, a product which is obtained either by fusing crystalline silica (SiO_2), which is quartz proper, or silica in some other form which is not crystalline. As I employ the term in the specified connection, quartz is synonymous with fused silica.

To prevent the action of mercury on the tube B, I interpose a barrier material G. Since fused silica as well as the glass of which the member C is constructed both have very low coefficients of expansion while the tube B and the leaf F have much larger coefficients of thermal expansion, it is necessary that the barrier G shall be constructed of a material which shall at all temperatures adapt itself and conform to the shape and dimensions of the different members A, C, B and F. To obtain this adaptability, in view of the fact that the different members possess greatly varying coefficients of expansion, the barrier material must possess the quality of yielding so as not to put any part under undue stress while at the same time forming contact with all. Throughout the specification and claims I shall employ the term "yielding quality" to designate the above described characteristic of the barrier material and to the barrier as a "barrier of yielding material". As barrier material I employ various materials such as semiplastic resin, either natural or artificial which at high temperatures possess just enough plasticity to yield to the volume changes imposed by thermal change of the various parts; a loosely fritted material, the minute particles of which adjust themselves as the temperature changes; or, what I prefer in most cases, a pulverulent material, such as ferric oxid, the interstices between the particles of which are so minute that even mercury vapor penetrates with extreme difficulty and slowness.

When a pulverulent material is employed as barrier, I retain it in its desired position by means of a suitable diaphragm. A seal so provided is shown in Fig. 3. Here, as in all the figures, corresponding letters are employed for corresponding parts. G is the barrier constructed of pulverulent material

which surrounds portions of the tube B and lead F and is contained within the tube A and sealing member C. To confine the material G to its proper place a diaphragm H is provided through which the lead F passes. The opening in H through which the lead passes is preferably made slightly larger than the lead so that it is not engaged thereby but slips freely. By this means the difference in expansion between F and A is provided for and no stress results on the seal itself owing to this cause.

Another variation of my invention is illustrated in Fig. 4. Here the diaphragm H engages a tubular metallic member I within which the lead F slides making contact therewith. The diaphragm may be constructed of a material that is introduced in the form of a powder or paste which is later baked into a more or less coherent mass. In some cases also, as shown in Fig. 5, the entire diaphragm I may be constructed of metal. The edge of the diaphragm in this case is preferably made thin so that it will not unduly stress the tube A. The tube A is further provided with an annular groove J which engages the edge of the diaphragm I.

What I claim and desire to secure by Letters Patent is:

1. In a vapor electric apparatus, a container constructed of non-conducting material, a metallic member sealed through the wall of the container, a barrier of yielding material interposed between the metallic member and the interior of the container for the purpose of intercepting the vapor or its liquid in order to protect the metallic member against deterioration.

2. In a vapor electric apparatus containing a vaporizable liquid, a seal comprising a tubular metallic member sealed through a vitreous envelop of lower coefficient of thermal expansion than that of the metallic tube, and means to intercept the vapor or liquid in order to prevent the deterioration of the metal tube thereby.

3. In a vapor electric apparatus containing a vaporizing fluid, a seal comprising a

tubular metallic member sealed through a vitreous member of lower coefficient of expansion than that of the tubular member, a barrier of yielding material interposed between the vapor or liquid and the tubular member to protect the said member against deterioration by the vapor or liquid.

4. In a vapor electric apparatus containing a vaporizable liquid, a seal comprising a tubular metallic member sealed through a vitreous member of lower coefficient of expansion than that of the tubular member, a lead extending into the interior of the vapor electric apparatus and a barrier of yielding material interposed between the liquid or its vapor and the tubular member and engaging the lead.

5. In a vapor electric apparatus comprising a metallic vapor, a container of non-conducting material, a tubular metallic member of higher coefficient of expansion than that of the container material, and sealed through the container wall, a barrier of yielding material interposed between the tubular metal member and the vapor or its liquid within the container to prevent the deterioration of the tubular member.

6. In a vapor electric apparatus, a container of fused silica and containing mercury, a metallic tube sealed through the walls of the container, a barrier of yielding material interposed between the interior of the container and the metallic tube to protect the tube against the action of mercury.

7. In a vapor electric apparatus, a container constructed of fused silica, and containing mercury, a platinum tube sealed through the wall of the container, a barrier of yielding material interposed between the interior of the container and the platinum tube to protect the tube against the action of mercury.

Signed by me at Boston, Massachusetts this twenty fifth day of February, 1913.

FREDERICK G. KEYES.
